UNITED STATES PATENT OFFICE

97,272

DESIGN FOR A CURTAIN FABRIC

Frederick Gentner, Philadelphia, Pa.

Application October 1, 1935, Serial No. 58,780

Term of patent 14 years

To all whom it may concern:

Be it known that I, Frederick Gentner, a citizen of the United States of America, residing in Philadelphia, county of Philadelphia, and State of Pennsylvania, have invented a new, original, and ornamental Design for a Curtain Fabric, of which the following is a specification, reference being had to the accompanying drawing, forming part thereof, wherein the figure is a plan view of a piece of curtain fabric showing my new design, a unit of which is included within dot and dash lines.

I claim:

The ornamental design for a curtain fabric, substantially as shown, and described.

FREDERICK GENTNER.
